CLAIM

The ornamental design for a gaming system having a gaming machine display and at least one spacer display, as shown and described.

DESCRIPTION

This application relates to the following co-pending commonly owned patent applications: “Gaming System Combined Shared Symbol Display and Protective Dome,” Ser. No. 29/253,516, “Gaming System Dome For A Shared Symbol Display,” Ser. No. 29/253,510, “Gaming System Having A Combed Dome and Display Device,” Ser. No. 29/253,514, “Gaming System Dome Cap For A Shared Symbol Display,” Ser. No. 29/253,518, “Gaming System Dome Cap For A Shared Symbol Display,” Ser. No. 29/253,561, “Gaming System Display,” Ser. No. 29/253,508, “Gaming System Combined Light Candle and Indicator For A Shared Symbol Display,” Ser. No. 29/253,513, “Gaming System Indicator For A Shared Symbol Display,” Ser. No.

29/253,511, “Gaming System Light Candle,” Ser. No. 29/253,517, and “Gaming System Having A Shared Symbol Display,” Ser. No. 29/247,063.

FIG. 1 is a front perspective view of a gaming machine display and a spacer display of the gaming system of our new design, that portion shown in phantom is not part of the design sought to be patented and is provided for environmental purposes only.

FIG. 2 is a top plan view of the gaming machine display and the spacer display of the gaming system of our new design illustrated in FIG. 1, that portion shown in phantom is not part of the design sought to be patented and is provided for environmental purposes only.

FIG. 3 is an elevated front view of the gaming machine display and the spacer display of the gaming system of our new design illustrated in FIG. 1, that portion shown in phantom is not part of the design sought to be patented and is provided for environmental purposes only.

FIG. 4 is a front perspective view of a gaming machine display and spacer displays of another embodiment of the gaming system of our new design, that portion shown in phantom is not part of the design sought to be patented and is provided for environmental purposes only.

FIG. 5 is a top plan view of the gaming machine display and spacer displays of the gaming system of our new design illustrated in FIG. 4, that portion shown in phantom is not part of the design sought to be patented and is provided for environmental purposes only; and,

FIG. 6 is an elevated front view of the gaming machine display and spacer displays of the gaming system of our new design illustrated in FIG. 4, that portion shown in phantom is not part of the design sought to be patented and is provided for environmental purposes only.
